his attorney.

UNITED STATES PATENT OFFICE.

LAWRENCE C. TURNOCK, OF EDGEWOOD, PENNSYLVANIA.

METHOD AND APPARATUS FOR COATING.

Application filed October 12, 1923. Serial No. 668,113.

To all whom it may concern:

Be it known that I, LAWRENCE C. TURNOCK, a citizen of the United States, residing at Edgewood, Allegheny County, Pennsylvania, have invented a new and useful Improvement in Methods and Apparatus for Coating, of which the following is a full, clear, and exact description.

The present invention relates broadly to 10 the coating of objects with metal, and more particularly to the coating by electro-deposition of different articles. The invention is especially adaptable to the production of electrolytes, wherein great accuracy of 15 weight and thickness is desirable, although the invention is not limited in this respect.

Heretofore in the formation of electrolytes, the thickness of the deposit has been determined by the sense of feel with wax 20 cases, and in other cases by a rough approximation based upon time. While some skilled operators are capable of judging the thickness of the deposit by the sense of touch with considerable speed and a fair degree 25 of accuracy, this method, like the other, is largely a matter of approximation only, and can not be applied at all where lead molds are used.

By the present invention, there is provided 30 a method and apparatus enabling a coating of the desired thickness to be applied, and then indicating, in some suitable manner, the attainment of this result. In this way, it is possible to obtain uniform results in the 35 shortest possible time and with the likelihood of error reduced to a minimum.

In the accompanying drawings, there is indicated more or less diagrammatically, 40 one form of apparatus by means of which my invention may be carried out, it being understood that the drawings are illustrative only and do not define the limits of the invention, as changes may be made therein as desired, without departing from the spirit 45 of my invention or scope of my broader claims.

In the drawings:

Figure 1 is a diagrammatic view, partly 50 broken away, illustrating a preferred embodiment of the present invention; and

Figure 2 is a detail view illustrating one of the switches employed.

In accordance with the present invention, there may be provided a tank 2, adapted to

receive a suitable bath for electrolytic deposition, as well understood in the art. Extending lengthwise of the tank and supported in any desired cooperative relation thereto may be a bus bar 3, adapted to be electrically connected to a series of anodes A 55 and A', any required number of which may be provided. Cooperating with the anode A may be a pair of cases C and C', serving as cathodes and adapted to receive the deposit, while cooperating with the anode A' 60 is a similar pair of cases C² and C³.

The operation of each of the anodes is the same, and the relationship between the anodes and the cathodes is identical. For this reason, it will only be necessary to fully 70 set forth the operation of a single anode and cathode, it being understood that both the anodes and cathodes may be stationary, or either one or both in motion.

In operation, current flows from a suitable 75 source of electric power to the bus bar 3, and thence to the anode A. From this anode, there is a current flow to the cathode case C and thence through the connection 4 to the wire 5. This wire is operatively connected to one terminal of an ampere-hour or 80 control meter 6, of any standard construction, such, for example, as the well known Sangamo meter, operating on a time current flow basis. It is well known that the amount 85 of metal deposited electrolytically is directly proportional to the current flow, so that by providing a predetermined current flow for a definite period of time, a deposit of known thickness per unit of surface area can be 90 produced. This makes it unnecessary to keep a separate record of the time each case 95 is immersed, or its switch closed, and makes it possible to start depositing on different cases at different times without keeping any time record thereof, and insures the simultaneous production of articles having either deposits of the same or different thicknesses, as desired.

The opposite terminal of the meter 6 is 100 electrically connected to the wire 7, leading to the fixed post 8 of a single pole, double throw switch 9. This switch is illustrated in detail in Figure 2. In its full line position, which is the position it normally occupies during the electrodeposition operation, it is in electrical connection with a contact 10, while in its upper dotted line

position, it is in electrical connection with a contact 11. In its intermediate dotted line position, the switch is in neutral position, cutting off all current flow.

5. The switch 9 in Figure 1 being in the full line position of Figure 2, permits the current to flow through the contact 10 to the bus bar 12. From the bus bar 12, the circuit is completed by bus bar 13 to the terminal 14 of a totalizing meter 15. This meter may be of the recording type, whose function is to add and maintain a permanent record of operation of all the separate control meters 6 on a single board, thus enabling a record to be kept of all metal used. From the meter 15, current flows to contact 16 and bus bar 17 to the bus bar 18, connected to the opposite side of the source of electric power.

20. From the foregoing, it will be apparent that with each of the switches in the position described, current will flow from each of the anodes to the respective cathode cases provided. If for any reason, it is desired to 25 determine the current flow to any particular cathode, the corresponding switch will be pulled to its upper dotted line position to bring it into electrical connection with the contact 11 and permit current to flow to the 30 bus bar 19. This bus bar is electrically connected to one terminal of an indicating meter 20, the opposite terminal of which is connected to the bus bar 13. In this manner, the flow of current between any anode and 35 cathode may be ascertained without interfering with the function of the meter 15. If desired, this indicating meter may have a special scale, in addition to the ampere scale, which will read in the corresponding 40 weight units of metal deposited per hour.

In order to indicate the operation of any particular cathode, there may be provided indicating means of suitable character, showing whether the switches 9 are closed 45 or open. While this indicating means may be visual or audible, I have indicated lamps for this purpose. With a switch closed, current will flow from bus bar 3 to wire 21, connected to each of the white lamps 50 1, 1', 1² and 1³ by separate lead wires 22, and connected to each of the red lamps L, L', L² and L³ by separate lead wires 23. The opposite side of each of the white lamps is connected by a lead 24 to the corresponding 55 wire 7. It will thus be obvious that with any switch in full line closed position, the corresponding white light will be lighted, thus indicating the flow of current to a particular cathode.

60. This indicating meter is desirable, as it serves to quickly indicate either proper or faulty operating conditions. For example, too low a current flow may indicate improper contact, too low bath potential or improper spacing of anode or cathode. Too

high a current flow, on the other hand, may indicate too high bath potential, improper anode and cathode spacing, contributing to inferior metal deposits.

The opposite side of each of the red lamps 70 may be connected by a lead 25 to a terminal 26 on its cooperating control meter 6. This terminal is in electrical connection, as indicated by dotted lines in Figure 1, with the pointer of the meter. In addition to the 75 regular pointer, there may be provided an auxiliary indicating hand 27, which can be manually moved to any position, the position selected depending upon the weight of metal to be deposited. With this construction, when the pointer reaches a position corresponding to that of the hand H, current will flow through such lamp and the pointer to the hand 27, electrically connected to the terminal 28. Each terminal 28 is, in turn, 80 connected to the corresponding meter wire 7. Thus, when the pointer of any meter 6 reaches a position coinciding with its auxiliary hand, both the white light and the 85 red light for such meter will be lighted. 90

Preferably, the connections are such that the lighting of any red light will indicate that a deposit of the desired thickness has been made on its corresponding cathode. This is accomplished by calibrating the 95 meters in any suitable manner, as for instance, to correspond to the weight of the metal deposited. As the weight of metal distributed over a given area controls the thickness, it is possible by initially setting 100 the auxiliary hand at the desired point to definitely indicate when such weight and thickness of metal has been deposited. As the movement of the pointer is dependent upon both time and current flow, it will 105 be apparent that when any pointer reaches a position coinciding with that of its auxiliary hand, the coating on a particular cathode will be completed. This will be shown not only by the position of such 110 pointer, but by the indicating means L, L', L² or L³. 115

With the present invention, the meter 15 will show the total metal deposited over any period of time, while the meter 20 makes 115 it possible to quickly show the individual current flow, or corresponding rate of metal deposition, to any one cathode. Any desired number of anodes and cathodes may be provided and the same results obtained. 120

It will be obvious that while I have herein referred to cases such as used in the electrotyping industry, the utility of the invention is not limited in this respect, but is 125 equally adaptable to controlling metal deposits to individual articles of any nature, such as now coated by other methods.

Further advantages arise from the provision of means making it possible to always secure a coating of any desired and prede-

terminated thickness. This insures uniformity in the deposit on the articles coated, irrespective of their nature or character.

Still further advantages arise from the provision of indicating means calling attention to the completion of the deposit on any cathode.

Still other advantages arise from the provision of means making it possible to obtain at any instant the current flow or rate of metal deposition to each individual article to be plated, thereby quickly indicating proper or improper operating conditions.

I claim:

15 1. In the method of electroplating, the steps consisting of submerging a plurality of articles to be coated as cathodes in a bath in cooperative relation to a source of coating metal, and separately indicating the deposit on each article.

20 2. In the method of electroplating, the steps consisting of submerging a plurality of articles to be coated as cathodes in a bath in cooperative relation to a source of coating metal, separately indicating the deposit on each article, and indicating the total metal deposited on all of said articles.

25 3. In the method of producing electro-types, the steps consisting of submerging a plurality of cases as cathodes in a bath in cooperative relation to at least one anode, and separately indicating the deposit on each case.

30 4. In the method of producing electro-types, the steps consisting of submerging a plurality of cases as cathodes in a bath in cooperative relation to at least one anode, separately indicating the deposit on each case, and indicating the total deposit on all of said cases.

35 5. In an apparatus for electroplating, a bath having at least one anode therein, a plurality of articles to be coated arranged as cathodes in cooperative relation thereto, and separate indicating means for each cathode.

40 6. In an apparatus for electroplating, a bath having at least one anode therein, a plurality of articles to be coated arranged as cathodes in cooperative relation thereto, and means for indicating the total metal deposited on all of said cathodes.

45 7. In an apparatus for electroplating, a bath having at least one anode therein, a plurality of articles to be coated arranged as cathodes in cooperative relation thereto,

separate indicating means for each cathode, and other means for indicating the completion of the coating operation.

60

8. In an apparatus for electroplating, a bath having at least one anode therein, a plurality of articles to be coated arranged as cathodes in cooperative relation thereto, separate indicating means for each cathode, and means adapted to be operatively connected at will to any of said cathodes for indicating the operation thereof.

65

9. In an apparatus for electroplating, a bath having at least one anode therein, a plurality of articles to be coated arranged as cathodes in cooperative relation thereto, and means adapted to be operatively connected at will to any of said cathodes for indicating the operation thereof.

70

10. In an apparatus for electroplating, a bath having at least one anode therein, a plurality of articles to be coated arranged as cathodes in cooperative relation thereto, separate indicating means for each cathode, means for indicating the total metal deposit on all of said cathodes, and means adapted to be operatively connected at will to any of said cathodes for indicating the operation thereof.

75

11. In an apparatus for electroplating, a bath having at least one anode therein, a plurality of articles to be coated arranged as cathodes in cooperative relation thereto, means for indicating the total metal deposit on all of said cathodes, and means adapted to be operatively connected at will to any of said cathodes for indicating the operation thereof.

80

12. In the method of electroplating, the steps consisting of providing a plurality of cathodes in a single bath in cooperative relation to a source of coating metal, and separately connecting a meter to each cathode.

85

13. As an article of manufacture, a current flow meter for use in electroplating, having a dial graduated to indicate the rate at which the metal is deposited.

90

14. The method of electroplating a plurality of articles in a plating bath, which includes dividing the articles among a plurality of cathodes in the same bath and separately measuring the quantity of metal deposited on each cathode.

100

In testimony whereof I have hereunto set my hand.

110

LAWRENCE C. TURNOCK.
